[57] CLAIM

The ornamental design for a doll cradle, substantially as shown and described.

DESCRIPTION

FIG. 1 is a front perspective view of a doll cradle showing my new design;

FIG. 2 is an end elevational view thereof;

FIG. 3 is a side elevational view thereof; and

FIG. 4 is a bottom plan view thereof.

Portions of the design have been omitted in FIG. 3 for ease of illustration.

FIG. 2

FIG. 3

FIG. 4
